[57] CLAIM

The ornamental design for a toy play house or similar article, as shown and described.

DESCRIPTION

FIG. 1 is a front perspective view of a toy play house or similar article showing our new design;

FIG. 2 is a rear perspective view thereof;

FIG. 3 is a side perspective view thereof with the door member removed for ease of illustration; and,

FIG. 4 is an end perspective view thereof, the end opposite being substantially a mirror image.

FIG. 1

FIG. 2

FIG. 3

FIG. 4
